UNITED STATES PATENT OFFICE.

GEORGE A. BELDING, OF BILLINGS, MONTANA.

JOINT FOR METAL CULVERTS OR THE LIKE.

1,395,253.

Specification of Letters Patent.

Patented Nov. 1, 1921.

Application filed March 31, 1920. Serial No. 370,214.

To all whom it may concern:

Be it known that I, GEORGE A. BELDING, a citizen of the United States, residing at Billings, in the county of Yellowstone and State of Montana, have invented certain new and useful Improvements in Joints for Metal Culverts or the like, of which the following is a specification, reference being had to the accompanying drawings.

10 This invention relates to culverts, and particularly to culverts made in sections of corrugated metal.

The general object of this invention is to provide improved means for connecting the 15 culvert sections to each other.

A further object is to provide connecting means which will permit these sections to be readily assembled or readily disassembled, the connecting means being so constructed as 20 to form the least possible obstruction on the interior of the culvert.

A further object is to provide an improved joint for connecting the sheet metal sections to each other.

25 Other objects will appear in the course of the following description.

My invention is illustrated in the accompanying drawings, wherein:

Figure 1 is a side elevation of a culvert 30 constructed in accordance with my invention;

Fig. 2 is a section on the line 2—2 of Fig. 1;

Fig. 3 is a section on the line 3—3 of 35 Fig. 1;

Fig. 4 is a sectional view taken on the same lines as Fig. 2, but showing a modification of the joint;

Fig. 5 is a section on the line 5—5 of 40 Fig. 1;

Fig. 6 is a section on the line 6—6 of Fig. 1;

Fig. 7 is a fragmentary sectional view of the longitudinal margin of one culvert section;

Fig. 8 is a like sectional view of the longitudinal margin of the opposed section;

Figs. 9 and 10 are face views of the two sections shown in Figs. 7 and 8;

50 Fig. 11 is a fragmentary section showing my invention applied to a culvert having a shape other than circular.

Referring to these drawings, it will be seen that I have illustrated in Fig. 1 a portion of 55 an ordinary circular culvert of corrugated sheet metal, wherein the upper section A at

its margin fits within the margin of the lower section B, and wherein the section A at its end fits over a section A' and the section B at one end fits over a section B', the joint between the sections B and B' being staggered relative to the joint between the sections A and A'.

For the purpose of connecting the margins of the upper sections A and A' to the margins of the lower sections B and B', I provide the upper sections at their margins with openings 10 arranged equi-distantly along the edge of the section, these openings, as shown in Fig. 9, being preferably somewhat elliptical in form. The section B or B' at its margins is provided with a more or less resilient and relatively thick, narrow tongue 11 on its inside face, which tongue is approximately rectangular in plan and is attached at its base to the sheet metal of the lower section by means of a rivet 12. Beyond this rivet the inner face of the tongue is spaced from the confronting face of the section, as at 13. In Fig. 2 this spacing is secured by off-setting the tongue. The face of the tongue confronting the inner face of the section is somewhat curved both longitudinally and transversely to fit the curvature of the circular pipe and fit between the corrugations of this pipe or culvert, and adjacent its free end has a screw-threaded perforation 14 which registers with a perforation 15 formed in the marginal wall of the lower section. When the upper section is placed in engagement with the lower section, the perforations 10 register with the perforations 15 and 14 to permit the passage of an attaching screw 16 having a many-sided head 17 whereby a wrench may be applied to 95 tighten up on the screw.

I do not wish to be limited to off-setting the tongue 11, as the same result may be accomplished by off-setting the margin of the metal forming the section to which the tongue is applied. Thus, in Fig. 4 the tongue 11 is not off-set, but the sheet metal of the section B is off-set, at 18, so as to provide a space for the reception of the margin of the opposed culvert section. Otherwise than this, the construction shown in Fig. 4 is identical with that shown in Fig. 2 and in Figs. 7 and 8.

It is obvious that ordinarily the margin of the upper section and the margin of the lower section will overlap so that there will be two plies of metal between the head 17 of

the screw 16 and the tongue 11. Where the two upper sections A and A' join, however, it is obvious that there will be three thicknesses of metal between the head 17 of the 5 screw and the tongue, as illustrated most clearly in Fig. 6, and the same is true of the joint between the sections B and B' and the section A.

The sections A and A' and the sections B 10 and B' will be connected at intervals by screws, bolts or other engaging devices. While I do not wish to be limited to any particular engaging devices, it will be obvious that the construction such as I have 15 shown in Figs. 2, 3 and 4 and 7 and 8 may be used for this purpose, that is the section A', for instance, be provided with a tongue such as the tongue 11 and the section A to be provided with a slot through which a bolt, 20 such as the bolt 16, passes into the tongue. I do not wish to be limited, therefore, to the use of the connections shown in Figs. 2, 3 and 4 and Figs. 7 and 8 for the purpose of connecting longitudinally extending sections, as this device may also be used for 25 the purpose of connecting sections end to end.

While the ordinary form of culverts is that of a circle, yet under some circumstances culverts will be formed with a flat bottom and a rounded top, as illustrated in Fig. 11, where the section B² is flat but has upwardly and inwardly turned side margins, while the section A² is arcuate. The same 30 form of fastening device is used, however, with these sections as with the completely arcuate sections, and I have illustrated the 35 construction shown in Fig. 11 merely for the purpose of indicating that my fastening 40 device might be applied to connecting the overlapping marginal edges of sections of any character, and that I do not wish to be limited to the use of these fastening devices for connecting semi-circular sections, nor 45 do I wish to be limited to the use of these fastening devices only on the longitudinally extending joints of a structure, as they may be used wherever one piece of sheet metal overlaps another.

50 I claim:

1. A structure of the character described including two overlapping sections, one of said sections being formed with a perforation in its wall and on its inside face being 55 provided with a relatively narrow and thick tongue extending parallel to the wall but spaced therefrom and formed with a perforation alining with the perforation in the

section, said tongue having a base of equal thickness with the body of the tongue and 60 attached to the wall of the section, the other section being formed with a perforation adapted to register with said perforations in the tongue and wall of the first named section, the perforation of the tongue being 65 screw-threaded, and a screw-threaded fastening device passing through the perforation in the two sections and into the screw-threaded perforation in the tongue and having 70 a relatively large head.

2. A culvert comprising a series of upper, transversely curved sections and a series of transversely curved, lower sections, said sections being transversely corrugated, the 75 ends of the upper sections being overlapped and the ends of the lower sections being overlapped, the longitudinal margins of the upper sections overlapping the longitudinal margins of the lower sections, the margins 80 of the upper and lower sections having alining perforations, a series of tongues attached at intervals along the margin of the lower section on the inside face thereof, said tongues on their faces confronting the lower section being longitudinally curved 85 and transversely rounded to conform to the corrugations thereof and formed with a screw-threaded opening, the portion of the tongue having a screw-threaded opening being spaced from the confronting face of 90 the lower section, and a headed screw passing through the perforations and into said screw-threaded opening whereby to draw the tongue and the sections into engagement 95 with each other.

3. A transversely corrugated culvert section having a relatively narrow, relatively thick tongue disposed on the inside face of the culvert section and having a base formed at one end whereby it is attached to the 100 culvert section, the remainder of the tongue outward of the base being spaced from the culvert section and being transversely rounded to conform to the corrugation thereof and that portion of the culvert section opposite 105 the tongue and the tongue being perforated, a headed screw adapted to be inserted through said perforations and having screw-threaded engagement with said tongue, and a coacting culvert section insertible between 110 the tongue and the first named culvert section and having a perforation for the passage of the screw.

In testimony whereof I hereunto affix my signature.

GEORGE A. BELDING.
